TIMER

Application filed July 11, 1931. Serial No. 550,185.

This invention relates to improvements in timers.

It is the object of the invention to provide a novel and improved timer for an internal combustion hammer or like engine wherein it is desirable that the timer be actuated directly from the piston; that the timer ride directly on the face of the piston as distinguished from any longitudinal groove therein; and that the timer contacts be normally open.

In the drawing:

Figure 1 is a vertical axial section through an internal combustion hammer equipped with a timer embodying this invention.

Figure 2 is a fragmentary section showing a modified piston construction.

Figure 3 is an enlarged plan view of the head of the piston used in the device shown in Figure 2.

Like parts are identified by the same reference characters through the several views.

In the particular device disclosed the cylinder 4 in which piston 5 reciprocates is provided with a jacket 6 having cooling fins 7 for radiating heat conducted thereto by a liquid in the jacket. The cylinder is provided with a detachable head 8 having a jacket extension 9.

An anvil 10 is mounted for limited reciprocation in the lower end of the cylinder, its movement being limited by the retainer 11 for tool 12. Compression spring 14 and 15 of different strength and characteristics encircle a hammer 19 carried by the piston and are of such strength as to be adapted to return the piston during its compression stroke. The purpose of heavier spring 14 is to provide a resilient seat for the active spring 15 whereby to absorb impact shocks of hammer 19 on anvil 10 which would otherwise crystallize the return spring.

Mounted on the cylinder below the combustion chamber portion thereof is a fuel tank 20 including unitarily a carbureting device or mixing valve at 21 from which manifold passage 22 leads through port 23 into the sub-piston compression space in cylinder 4, thence transfer passage 24 leads through the cylinder casting to an inter-

mediate point in the cylinder wall uncovered by the movement of piston 5 in the course of its reciprocation for the delivery of a charge to the combustion chamber in the usual way.

Ignition of the charge in the combustion chamber is effected by means of the usual spark plug 25 under control of the timer mechanism now to be described.

Within timer case 26 on the wall of the cylinder is a grounded contact 27 adjustable in the path of oscillation of a moving contact 28 carried by a lever 29 pressed by spring 30 toward contact closing position. The lever is normally held in contact opening position by a plunger 31 which acts as a cam follower to ride upon a cam integral with the piston. The cam follower plunger 31 is preferably provided with an antifriction roller 32.

To avoid longitudinal channeling of the piston across the transfer passage 24 I prefer that the roller 32 should ride directly on the face of the piston throughout most of the piston movement. A shallow notch or groove 33 is disposed in the side of the piston skirt near the lower end thereof to receive the roller momentarily just before the piston reaches the top of its stroke. This disposition of the parts not only gives proper timing but ensures that the contacts will not be closed when the piston is at rest, nor at any other time except incident to properly timed ignition.

In the Figure 1 construction the notch or groove 33 will be understood to have no appreciable peripheral extent and in order to maintain it in angular registry with the cam follower I provide elsewhere in the piston a longitudinal groove at 35 with which a centering pin 36 is engaged.

The construction shown in Figure 2 is similar to that described with the exception that the groove 33' extends peripherally completely around the piston 5. This arrangement makes the groove 35 and pin 36 unnecessary but requires the use of a peculiar baffle 37 on the piston head with radial wings 38 so arranged that in any rotative position of the piston such wings will intercept the path of the charge entering the cylinder.

through transfer passage 24 to prevent such charge from passing directly through the exhaust port 39.

I claim:

6. 1. The combination with an engine cylinder and a piston having a relieved peripheral surface, of a timer deriving motion directly from the piston and comprising a fixed contact, a movable contact, and a cam follower 10 connected with the movable contact and riding directly on the piston, whereby to maintain said contacts open pending registry with said cam follower of the relieved portion of the piston.
- 15 2. The combination with relatively fixed and movable timing contacts, of a cam follower connected with a moving contact and an engine piston with which said cam follower is directly engageable, the connection between 20 said cam follower and moving contact being of such a length as to maintain said contacts normally separated and said piston being provided with a peripheral recess of such 25 limited axial extent as to permit the cam follower only momentary engagement in the recess for the closing of said contacts in the movement of the piston.
3. The combination with a pair of relatively movable timing contacts and a contact 30 actuator comprising a cam follower, of a cylinder upon which said cam follower is mounted for reciprocation, and a piston operable in the cylinder and provided with a generally cylindrical surface upon which said cam follower 35 normally rides, said piston having a relieved peripheral portion registerable with the cam follower adjacent one extreme piston position and adapted to permit sufficient movement of the cam follower to close the timer contacts.
- 40 4. The combination with a pair of relatively movable timing contacts and a contact actuator comprising a cam follower, of a cylinder upon which said cam follower is mounted 45 for reciprocation, and a piston operable in the cylinder and provided with a generally cylindrical surface upon which said cam follower normally rides, said piston having a relieved peripheral portion registerable with 50 the cam follower adjacent one extreme piston position and adapted to permit sufficient movement of the cam follower to close the timer contacts, together with means for confining said piston against angular displacement, its relieved peripheral portion being of 55 limited peripheral extent.

5. The combination with a pair of relatively movable timer contacts and a contact actuator normally maintaining said contacts 60 separated and comprising a cam follower, of a piston provided with a peripheral groove registerable with said cam follower and a generally cylindrical surface upon which said cam follower rides except when engaged 65 in said groove, said piston being reciprocable

in the cylinder and freely rotatable with respect thereto.

6. The combination with a pair of relatively movable timer contacts and a contact actuator normally maintaining said contacts 70 separated and comprising a cam follower, of a piston provided with a peripheral groove registerable with said cam follower and a generally cylindrical surface upon which said cam follower rides except when engaged in 75 said groove, said piston being reciprocable in the cylinder and freely rotatable with respect thereto, together with a baffle on the top of said piston effective to interrupt gasoline movement across the face of the piston irrespective of the angular position thereof.

7. In a two cycle engine, the combination with a cylinder having transfer and exhaust ports, of a piston reciprocable across said ports and rotatable within the cylinder, said 80 piston being provided with a peripheral groove in its skirt portion, and a baffle on its face between said ports effective in any angular position of the piston, a cam follower reciprocable through the cylinder wall and 85 adapted to ride on the face of the piston and into the groove of its skirt, and a pair of normally separated relatively movable contacts supported on the cylinder, one of said contacts being connected with said cam follower 90 for engagement with the other contact when said cam follower rides into the piston groove.

8. In a device of the character described, the combination with a cylinder a piston reciprocable therein and provided in its skirt 100 with a groove of limited axial and peripheral extent, means restricting said piston against rotation in the cylinder, a cam follower riding on the face of the piston in registry with said groove, and timer contacts mounted on the piston, one of which is connected with said cam follower for engagement with the other contact when said cam follower rides into the piston groove.
